PROCESS FOR CRACKING PETROLEUM OIL

Original Filed Feb. 7, 1923

UNITED STATES PATENT OFFICE

AUBREY D. DAVID, OF CHICAGO, ILLINOIS, ASSIGNOR TO THE UNIVERSAL OIL PRODUCTS COMPANY, OF CHICAGO, ILLINOIS, A CORPORATION OF SOUTH DAKOTA

PROCESS FOR CRACKING PETROLEUM OIL

Application filed February 7, 1923, Serial No. 617,447. Renewed September 14, 1928.

This invention relates to improvements in a process for converting petroleum hydrocarbons of a relatively high molecular weight to those of a lower weight, the latter having the characteristics of gasoline.

Among the objects of the invention are to provide a process in which the reflux condensate separated out during the dephlegmating of the vapors is cooled prior to re-cycling, and its heat transferred to the raw oil to preheat the same; to provide a process in which the heat of the reflux condensate is also utilized to redistill the pressure distillate which is recycled through the heating stage through which the hot reflux is circulated, and to provide an apparatus for carrying out this process.

The single figure is a diagrammatic view of the plant, certain of the elements being reduced in scale and placed in a convenient position so as to more clearly bring out the details of the piping.

Referring to the drawing, the raw oil to be treated is introduced from any convenient source such as the reservoir or tank 1, and is directed through the pipe 2 controlled by the valve 3 to a pressure pump 4 from which it is discharged through the line 5 controlled by the valve 6 through a coil 7 positioned in a chamber 8 through which the hot reflux is circulated as hereinafter explained. From the discharge end of the coil, the preheated oil passes through the pipe 9 regulated by the valve 10, and is conducted through the charging line 11 to the heating coils 12 positioned in the side fired furnace 13, which is preferably heated by means of gas burners, not shown.

The oil after circulating through the furnace is raised to a conversion temperature, and is directed through the transfer line 14 controlled by the valve 15 to the expansion chamber 16.

The expansion chamber is equipped with try-cocks 17 for ascertaining the liquid level, and residuum drawoff lines 18 controlled by valves 19. The residuum lines are positioned at different heights on the chamber so as to facilitate the withdrawal of the un-vaporized and residual substances, should the

carbon accumulate and clog one of the lower lines.

The vapors evolved in the chamber pass off through the vapor pipe 20 regulated by the valve 21 to the dephlegmating or refluxing column 22 where they are caused to pass in a circuitous travel due to the positioning of baffle or perforated plates 23 in the column. During this dephlegmating or refluxing period the higher boiling point oil constituents are separated from the vapors and collect in the bottom of the column while the still vaporized portion passes off from the top of the column through the line 24. The refluxed condensate separated out in the dephlegmating stage, is drawn off from the lower part of the column through the pipe 25 regulated by the valve 26, and is directed to the lower compartment 8 in which is positioned the preheating coil 7. In this compartment heat is extracted from the reflux condensate by the passage of the cool charging stock through the coil 7 positioned in the compartment. From the bottom of this tank or compartment 8, the oil is withdrawn through the line 27 controlled by the valve 28, and is directed to a separate lower division or partitioned compartment 29. After being relieved of further heat in this chamber, the reflux condensate is drawn off through the line 30 regulated by the valve 31, and is charged by the pump 32 back into the heat coils through the pipe 11. The cooling of the reflux in this manner permits its being recharged into the system by positive means such as a pump shown at 32. It has been found that it is very difficult to handle reflux due to its high temperature when taken directly from the refluxing stage and recycled, but by extracting or relieving the reflux of its heat in separate cooling stages, the temperature is reduced to an extent where it may be easily recycled.

Returning to the vapors which are withdrawn from the top of the dephlegmator through the pipe 24, these vapors are directed to a chamber 33 in which is positioned a coil 34. This coil contains recycled pressure distillate as hereinafter explained, and relieves the vapors of their heat causing condensation

of certain of the relatively higher boiling point fractions.

The fluid oil constituents from the chamber 33 pass through the pipe 35 controlled by the valve 36 to a second chamber or compartment 37 in which is positioned a cooling coil 38. Water or cool oil may be circulated through this coil in order to subject the still vaporized constituents to a final condensing action. The distillate and gases pass from this chamber through the pipe 39 to the distillate receiver 40 which is equipped with a pressure relief valve 41, pressure gauge 42, liquid level gauge 43, and a drawoff line 44 controlled by a valve 45. The drawoff line communicates with a pressure distillate storage tank 46.

The distillate from the storage tank may be withdrawn through the line 47 controlled by the valve 48 and recycled by means of the pump 49 and line 50 through the coils 51 positioned in the chamber 29, and the coil 34 positioned in the chamber 33. This recirculation of the pressure distillate through the chambers in which the reflux condensate and heated oil vapors from the top of the dephlegmator are circulated, serves to increase the temperature of the recycled distillate prior to its being introduced through the line 52 controlled by the valve 53 to the still 54.

In this still the pressure distillate is redistilled under atmospheric pressure, and the vapors dephlegmated in the tower 55 and passed through the line 56 controlled by the valve 57 to the condenser 58 from which it is drawn off through the line 59, when it is in condition for refining.

In place of the single still, as shown at 54, a battery of stills may be used to retreat the recycled pressure distillate.

From the drawing, it is obvious that the process is economical in operation, as the heat in the reflux condensate is utilized to preheat the raw oil, and in addition reheat the pressure distillate prior to its being redistilled.

Also, in place of subjecting the vapors immediately to a final condensing action, a portion of their heat is extracted by the recirculation of the pressure distillate through a stage in which the hot vapors are circulated.

The extraction of the heat from the reflux condensate also permits a positive recirculation by means of the pressure pump, and permits the raising of the velocity of the oil in the heating tubes, or an increase in pressure over that maintained in the vaporizing chamber by controlling these differential pressures by the valve 15.

Heretofore, where the velocity and pressure of the recirculated reflux was dependent upon the height of the head maintained by the height of the dephlegmator, the velocity and pressure was limited, but with the means

for positive recirculation, a more accurate control may be obtained.

I claim as my invention:

A process of treating hydrocarbon oil consisting in continuously passing the oil through a heating zone wherein it is raised to a conversion temperature, in discharging the oil into an expansion zone wherein substantial vaporization occurs, in passing the vapors issuing from said expansion zone to a dephlegmator, in condensing the dephlegmated vapors as pressure distillate in passing the hot reflux condensate from said dephlegmator to a zone of heat interchange through which the incoming raw oil is passed, in withdrawing the reflux condensate from said zone of heat interchange and in returning it under applied pressure to the heating zone for retreatment, in redistilling the pressure distillate and in utilizing the heat of the vapors issuing from the dephlegmator to preheat the pressure distillate prior to such redistillation.

AUBREY D. DAVID.
